REUBEN WILLIAM TARRANT, OF LONDON, ENGLAND.

RAILWAY AND LIKE SIGNALING.

1,280,582.

Specification of Letters Patent.

Patented Oct. 1, 1918.

Application filed February 12, 1916. Serial No. 77,846.

To all whom it may concern:

Be it known that I, REUBEN WILLIAM TARRANT, a subject of the King of Great Britain, and resident of 26 Voltaire road, 5 Clapham, London, England, have invented certain new and useful Improvements in Railway and like Signaling, of which the following is a specification.

This invention relates to an improved rail-circuit system of electric control for railway traffic, consisting of two distinct so-called "rail-circuits" whereof the individual track-rails respectively form parts in series with the respective windings of a relay having 10 two separate windings; said rail-circuits being, normally, mutually independent and supplied with current from a single source, and the circuit of said source being closed through both track-rails in series with one 15 another only when said rails are connected together electrically, as for example in consequence of the presence of a train upon the rails.

The improved system comprises, for each 20 block-section of the line, a relay having two separate windings one end of each of which is connected to a source of current through one of the track-rails of the block-section, while the other end of each winding is connected to said source by a separate wire; the 25 arrangement being such that the magnetic fields normally produced by the energization of the respective windings coöperate so as to maintain the controlled signal in a pre-determined condition (say, "line clear"), whereas, on the occurrence of abnormal current-conditions within the system, the effect of the resultant magnetic field or fields (if any) is such that reversal of the condition 30 of the controlled signal (which will now indicate, say, "line blocked") is concurrently brought about.

The relay above referred to may be regarded as constituting either an electric motor, or a relay such as, for example, that described in the specification of Letters Patent of the United States 1,168,438 dated January 18, 1916.

In the accompanying drawing, which illustrates diagrammatically one arrangement embodying the present invention as applied to a single block-section of a line of railway, Figure 1 indicates the conditions normally existing in the system, and Fig. 2 indicates the conditions resulting from the entrance of a train into the block-section.

a, b are the rails of the track within the

block-section illustrated. *c* are the coils of one winding of the relay, and *d* are the coils of the other winding of the same. The pole-pieces *d*¹ of the winding *d* are stationary, whereas the pole-pieces *c*¹ of the winding *c* are pivoted so as to be movable toward and from the stationary pole-pieces *d*¹ and tend to approach the latter under gravity or spring-pressure. *e* is a source of current (hereinafter referred to as the battery, but it might be any other source of current, direct or alternating) for energizing the windings *c* and *d*, this source being placed toward one end of the block-section and the relay toward the opposite end.

One pole (say, the positive pole) of the battery *e* is connected by a wire 11 to the rail *a* at or near the adjacent extremity of the section, the same rail being connected, at or near the opposite extremity of the section, by a wire 12 to one end of the winding *d* of the relay; while the other end of this winding is connected by a wire *d*² to the opposite pole (say, the negative pole) of the battery *e*. This latter pole of the battery is connected by a wire 13 to the rail *b* at or near the adjacent extremity of the section, the same rail being connected, at or near the opposite extremity of the section, by a wire 14 to one end of the winding *c* of the relay; while the other end of this winding is connected by an insulated wire *c*² to the first-mentioned (or positive) pole of the battery *e*.

f is an electrically actuated or governed signal commanding the admission of traffic to the block-section, the electric circuit upon which the condition of the signal is dependent being indicated as fed from a battery or other source *g*. In the circuit of this battery and the signal are interposed two switches *h* and *j*, which are respectively so controlled by the movable pole-pieces *c*¹ of the winding *c* of the relay that, so long as both the pole-pieces *c*¹ are held apart from the stationary pole-pieces *d*¹ of the winding *d*, the switches *h* and *j* are closed and the circuit of the battery *g* and signal *f* is closed and the signal is thus held at "line clear" as indicated in Fig. 1; whereas, on either or both of the pole-pieces *c*¹ approaching the pole-pieces *d*¹, the circuit of the battery *g* and signal *f* is broken at either or both of the switches *h* and *j*, and the signal is thus put to "line blocked" as indicated in Fig. 2.

k (Fig. 2) indicates an axle and pair of

wheels of a train in the block-section and serving to connect together electrically the rails *a* and *b*.

m is a resistance interposed between the 5 battery *e* and the rail *a* for the purpose of preventing excessive increase of current-value when, owing for example to the presence of an axle and pair of wheels in the block-section as in Fig. 2, the battery *e* is 10 short-circuited across the rails *a* and *b*. The resistance *m* may be a thermal auto-resistance whereof the value will rise in proportion, substantially, with any increase in the current passing through it. In any case the 15 normal value of the resistance *m* should be so adjusted as to maintain the proportion, between the current-values in the windings *c* and *d* respectively, required for normally causing the pole-pieces *c*¹ to be repelled and 20 held apart from the pole-pieces *d*¹, as will now be described with reference to Fig. 1.

That is to say, in normal circumstances (i. e. when no train is in the block-section, and no other abnormal current-conditions 25 prevail), current flows from the positive pole of the battery *e*, through the wire 11, resistance *m*, rail *a*, wire 12, winding *d*, and wire *d*², back to the negative pole of the battery *e*, thus energizing the winding *d* of the relay. At the same time current also 30 flows from the positive pole of the battery *e*, through the wire *c*², winding *c*, wire 14, and wire 13, back to the negative pole of the battery *e*, thus energizing the winding *c* of the 35 relay. The respective coils of the relay are so wound that, so long as the conditions just described prevail, each of the poles *d*¹ has opposite to it a pole *c*¹ of the same sign, so that the movable poles *c*¹ are repelled and 40 held apart from the stationary poles *d*¹ in opposition to gravity or spring pressure. Consequently, the switches *h* and *j* are closed and the signal *f* is held at "line clear," as indicated in Fig. 1.

45 If, now, as indicated in Fig. 2, an axle and wheels *k* enter the block-section, it will be seen that whereas, on the one hand, the circuit of the battery *e* through the winding *c* of the relay remains substantially unaffected, current still flowing from the positive pole of the battery through the wire *c*², winding *c*, wire 14, rail *b*, and wire 13 back to the negative pole of the battery, on the other hand the presence of the axle and 55 wheels *k* has for effect to cut off current, partially or wholly, from the winding *d* of the relay, current now flowing from the positive pole of the battery *e* through wire 11, resistance *m*, part only of the length of 60 rail *a*, the wheels and axle *k*, the corresponding part only of the length of rail *b*, and wire 13, back to the negative pole of the battery. Hence, the winding *d* being partially or completely de-energized, the magnetic field between the pole-pieces *d*¹ becomes

weakened or ceases to exist, so that the repulsive effort previously maintained as between the pole-pieces *d*¹ and *c*¹ either ceases altogether or is so reduced as to be no longer capable of overcoming the gravity or spring-pressure under which the pole-pieces *c*¹ tend to approach the pole-pieces *d*¹, with the result that the switches *h* and *j* are no longer held closed and the signal *f* will be put to "line-blocked." 70

A like result as regards the switches *h* and *j* and signal *f* will be produced not only if current entirely ceases to flow in both of the windings *c* and *d*, but also if the current flowing in one only of the windings ceases, 80 or if the ratio between the values of the currents flowing in the respective windings is caused to vary beyond what may be termed the working limits of said ratio. Moreover, as any such disturbance of the current-conditions within the system (as distinct from total cessation of current in both windings of the relay) will produce a corresponding alteration in the strength of the magnetic field normally existing between the pole-pieces of the one winding relatively to the strength of the field normally existing between the pole-pieces of the other winding, the result of the disturbance may even be that the attractive influence of that magnetic field which tends to draw the pole-pieces *c*¹ toward the pole pieces *d*¹ may become so much more powerful than the repulsive influence of that field which tends to separate said pole-pieces, that the attractive influence of the first-mentioned magnetic field will co-operate with gravity or spring-pressure in holding the pole-pieces *c*¹ positively in position to keep the switches *h* and *j* open. 95

It will be observed that the arrangement as a whole involves the use not of a "track-circuit" (in the ordinary or accepted sense of a circuit whereof both rails of the track, being constantly in series with one another, 110 normally form a portion), but of two distinct "rail-circuits" whereof the individual track-rails *a* and *b* respectively form parts in series with the respective windings *d* and *c* of the relay; these "rail-circuits" being, 115 normally, mutually independent though supplied with current from a single source *e*, and the circuit of said source being closed through both track-rails *a* and *b* in series with one another only when said rails are 120 electrically connected together, as for example in consequence of the presence of a train in the block-section as at *k*.

What I claim is:—

1. In a system of electric control for railway traffic, the combination of a pair of track-rails, a source of electric energy whereof the opposite poles are connected to the respective track-rails at one end of the block-section, a relay, two separate wind- 125 130

- ings on said relay, each of which is connected in series between one pole of said source of energy and the opposite end of that track-rail which is connected to the 5 other pole of said source, and pole-pieces for each winding of the relay, the pole-pieces of the one winding being opposed to and movable toward and from the respectively adjacent pole-pieces of the other winding 10 and the respective windings being wound for producing normally a state of magnetic repulsion between each pole of the one winding and the opposed pole of the other winding.
- 15 2. In a system of electric control for railway traffic, the combination of a pair of track-rails, a source of electric energy whereof the opposite poles are connected to the respective track-rails at one end of the 20 block-section, an electric resistance interposed in series between one of said track-rails and the connected pole of said source of current, a relay, two separate windings on said relay each of which is connected in 25 series between one pole of said source of energy and the opposite end of that track-rail which is connected to the other pole of said source, and pole-pieces for each winding of the relay, the pole-pieces of the 30 one winding being opposed to and movable toward and from the respectively adjacent pole-pieces of the other winding and the respective windings being wound for producing normally a state of magnetic repulsion 35 between each pole of the one winding and the opposed pole of the other winding.
3. In a system of electric control for railway traffic, the combination of a pair of track-rails, a source of electric energy 40 whereof the opposite poles are connected to the respective track-rails at one end of the block-section, an electric resistance interposed in series between one of said track-rails and the connected pole of said source 45 of current, a relay adjacent to the opposite end of the block-section, two separate windings on said relay, one end of each winding being connected to the adjacent end of one of the track-rails, insulated conductors for 50 connecting the other ends of the respective windings with the respective poles of the source of energy, and pole-pieces for each winding of the relay, the pole-pieces of the one winding being opposed to and 55 movable toward and from the respectively adjacent pole-pieces of the other winding and the respective windings being wound for producing normally a state of magnetic repulsion between each pole of the one wind-
- ing and the opposed pole of the other winding. 60
4. In a system of electric control for railway traffic, the combination of a pair of track-rails, a source of electric energy whereof the opposite poles are connected to the 65 respective track-rails at one end of the block-section, an electric resistance interposed in series between one of said track-rails and the connected pole of said source of current, a relay, two separate windings 70 on said relay each of which is connected in series between one pole of said source of energy and the opposite end of that track-rail which is connected to the other pole of 75 said source, pole-pieces for each winding of the relay, the pole-pieces of the one winding being opposed to and movable toward and from the respectively adjacent pole-pieces of the other winding and the respective windings being wound for producing normally a state of magnetic repulsion between each pole of the one winding and the opposed pole of the other winding, an electrically-controlled signal, a source of electric energy for operating said signal, and 80 electric switches interposed in series between said source of energy and the signal, said switches being adapted to be controlled by the movable pole-pieces of the relay. 85
5. In a system of electric control for railway traffic, the combination of a pair of track-rails, a source of electric energy whereof the opposite poles are connected to the respective track-rails at one end of the block-section, an electric resistance interposed in series between one of said track-rails and the connected pole of said source of current, a relay, two separate windings 90 on said relay each of which is connected in series between one pole of said source of energy and the opposite end of that track rail which is connected to the other pole of said source, pole-pieces for each winding of the relay, the pole-pieces of the one winding being opposed to and movable toward 95 and from the respectively adjacent pole-pieces of the other winding and the respective windings being wound for producing normally a state of magnetic repulsion between each pole of the one winding and the opposed pole of the other winding, an electrically-controlled signal, a source of electric energy for operating said signal, and electric switches interposed in series between said source of energy and the signal, said switches being normally held closed by 100 the movable pole-pieces of the relay. 105
